CLAIM

The ornamental design for a faucet valve with safety handle, as shown.

DESCRIPTION

FIG. 1 is a left side elevational view of a faucet valve safety handle showing my new design, the right side elevational view is an identical mirror image;

FIG. 2 is a front elevational view thereof;

FIG. 3 is a top plan view thereof;

FIG. 4 is a bottom plan view thereof; and,

FIG. 5 is a rear elevational view thereof.

The broken line showing is for illustrative purposes only and forms no part of the claimed design.
